UNITED STATES PATENT OFFICE.

WILLIAM DIETER, OF NEW YORK, N. Y., ASSIGNOR TO E. W. BLISS COMPANY, OF BROOKLYN, NEW YORK, A CORPORATION OF WEST VIRGINIA.

DIVING-GEAR FOR TORPEDOES.

1,190,871.

Specification of Letters Patent.

Patented July 11, 1916.

Application filed March 13, 1916. Serial No. 83,738.

To all whom it may concern:

Be it known that I, WILLIAM DIETER, a citizen of the United States of America, residing in borough of Brooklyn, county of Kings, city and State of New York, have invented certain new and useful Improvements in Diving-Gear for Torpedoes, of which the following is a specification.

This invention relates to the depth or immersion mechanism for automobile torpedoes commonly known as the diving gear. This mechanism includes a hydrostat and pendulum connected together through levers and thence to the valve of the horizontal steering engine (or to the controlling element of any equivalent steering mechanism), so that the latter is operated by movements which are the resultant of the movements of the pendulum and of the moving member of the hydrostat. The hydrostat ordinarily comprises a diaphragm receiving on one side the hydrostatic pressure due to the depth of immersion and on the other side the adjustable pressure of a spring or springs.

The present invention is designed to improve the construction of such diving gear in order mainly to facilitate the removal of the hydrostat diaphragm from the exterior of the torpedo without the necessity of removing the entire steering unit, which latter comprises the mechanism for steering both in horizontal and vertical planes.

The invention will be best understood with reference to the accompanying drawing, showing the practical embodiment thereof, in which,—

Figure 1 is a side elevation of the after-part of a torpedo, partly broken away to show the diving mechanism in elevation. Fig. 2 is a view of the diving mechanism on a larger scale, being partly in elevation and partly in vertical mid-section. Fig. 3 is a diagrammatic view designed to show the connections and movements more clearly. Fig. 4 shows a fragment of Fig. 2, the part F being removed. Fig. 5 is a fragmentary inverted plan showing part of the ring for clamping the diaphragm.

The general construction of diving gear, upon which the present invention is an improvement, is that shown in the patent of Leavitt, No. 1,080,116, granted December 2, 1913, to which reference may be made for an illustration and description of those parts

which form no part of the present improvement, and which accordingly are not herein shown or described.

Referring to Fig. 1, A is the hull of the torpedo, B the diving rudder, B' its tiller, C the tiller rod leading to the piston or plunger of the engine or servo-motor D, and E the valve stem which operates the internal valve of the servo-motor. It is understood that motors or engines of this type have a so-called "floating plunger," being so controlled by the valve that every movement of the valve is followed by a corresponding movement of the plunger. Consequently the movements imparted to the stem E are quickly repeated by the tiller rod C.

The stem E is connected, as usual, to the upper arm of a lever F, being a floating lever in that it has no fixed fulcrum. This lever is technically called the whiffletree. It is fulcrumed at its middle at a point a upon a movable support G and its lower arm is connected by a rod H to the pendulum J. The fulcrum point a is connected indirectly to the hydrostat. The latter comprises a diaphragm K clamped fast to a shell or base L, so as to cover an opening therein. The outer face of the diaphragm is exposed to hydrostatic pressure in the chamber L' which has open communication with the sea. The upper side of the diaphragm receives the pressure of a spring or springs M.

In place of the connections heretofore provided between the diaphragm K and the fulcrum point a, the present invention provides a different series of connections. These comprise a lever P fulcrumed at b to a fixed point, having a pivotal or rocking connection c with the stem d of the diaphragm, and connected at its opposite free end d' with a small plunger or stem e which is movable vertically through a bushing f in the base L. The connection between d and e is best made as shown by providing the plunger e with two collars between which the rounded end d' acts. The upper end of the plunger is pivoted to a link g (preferably curved to clear the fulcrum bearing h of the rocking support or lever G); the upper end of this link is jointed to one arm of an elbow lever i pivoted at j. The pivots h and j are fixed pivots shown as mounted on a rigid bracket.

arm *k*, projecting from a fixed shell *N* (which in the torpedo as constructed contains the gyroscope). The other arm of the lever *i* is upturned and is connected by a link *m* with a stud *n* on the rock lever *G* below its upper end which carries the floating fulcrum *a* of the whiffletree *F*. For convenience the link *m* is made of adjustable length by constructing it with a screw-threaded rod *p*, the opposite ends of which screw into blocks *q* *q'*, which are pivoted respectively to the elbow lever and rock lever.

The essential relations of the parts and their operation may be best understood by reference to the diagram, Fig. 3, in which the parts are slightly re-arranged to show their relations more clearly, and the link *y* and link *m* are shown as straight links. It being understood that the points *b* *h* and *j* are fixed fulcrums for the levers *P* *G* and *i* respectively, the operation may best be understood by assuming that the torpedo in its run has attained too low a depth, so that the hydrostatic pressure forces upwardly the diaphragm *K*. This pulls up the pivot point *c* and rocks the lever *P*, lifting its free end *d'* and raising the plunger *e* which pushes up through the link *g* and rocks the lever *i*, exerting a pull through the link *m* to swing the rock lever *G* toward the right. The effect of this is to displace to the right the floating fulcrum *a* of the whiffletree *F*. As the pendulum *J* is assumed to remain undisturbed, its connection through the rod *H* with the lower end of the whiffletree holds the pivotal connection between the latter and the whiffletree stationary; the whiffletree, therefore, swings around its lower pivot as a fulcrum, and its upper arm executes a multiplied movement to the right which pushes through the rod *E* to move the valve aftward, which causes the plunger in following this movement to transmit to the rudder *B* an upward inclination. This steers the torpedo to a higher level, and if the torpedo runs higher than the set depth, a reverse series of movements results. The pendulum has its usual function of acting through the steering mechanism to tend to bring the torpedo to an even keel. In short, the operation is precisely the same as with the mechanisms heretofore provided, as shown for example in the Leavitt patent above-cited.

The new mechanism has an important advantage in that it permits of the ready removability of the diaphragm *K*. To this end the diaphragm is clamped beneath to the plate portion of the base *L* bounding the hydrostat opening. It is so clamped by means of a ring *r* fastened by a series of screws accessible from beneath. The fulcrum pivot *b* may be mounted in said ring or preferably on a separate pivotal piece *s*

screwed fast beneath the ring (see Fig. 5). To remove the diaphragm, it is only necessary to first remove the usual bottom plate *t* forming a continuation of the hull of the torpedo, then to disconnect the fulcrum piece *s*, whereupon the lever *P* may be taken away, its forked rounded end *d'* slipping out from between the collars of the plunger *e*; then by removing the fastening screws of the ring *r* the latter may be taken away with the diaphragm and diaphragm stem or plunger.

Heretofore movement has been communicated from the diaphragm to the whiffletree fulcrum by means of a rock lever, one arm of which is located within the chamber *L'* and the other arm above the base *L* within the torpedo, the two being connected by means of a rock shaft passing through a stuffing box. The stuffing box connection has at times leaked and at other times been made too tight, so that it worked with undue resistance, and in case of any accident there was liability that the parts would become bent, so that the rock shaft would bind in its stuffing box. These disadvantages are entirely overcome by communicating the movement from the exterior or water chamber to the interior or air chamber of the torpedo by means of the rising and falling plunger *e*. This is made to work with a free but practically watertight fit through the bushing *f*, thereby avoiding the frictional resistance of a stuffing box. There is practically no in-leakage of water between the plunger and bushing because almost immediately after the launching of the torpedo the exhaust air from the engine or turbine establishes an internal pressure which partially balances the external hydrostatic pressure, so that with the very slight clearance provided no material leakage can occur.

The adjustable provisions of the link *m* afford a convenient means of effecting fore and aft adjustment of the whiffletree fulcrum, and thereby of bringing the valve to its proper working position.

The construction may be varied and the parts re-arranged without changing the operation or departing from the invention, as hereinafter claimed.

The invention is applicable to the different arrangement of connections set forth in my Patent No. 1,145,355, granted July 6, 1915, when it is desired to bring about the mode of operation therein set forth.

What I claim is:—

1. In a diving gear for a torpedo, a hydrostat diaphragm detachable from the exterior, having an outer attaching ring, and a detachable lever for communicating movements from said diaphragm.

2. In a diving gear for a torpedo, a hydrostat diaphragm removable from the ex-

- terior, an attaching ring therefor, and a lever, the fulcrum of which is carried by said ring, and which lever receives movement from the diaphragm.
- 5 3. In a diving gear for a torpedo, the combination with a hydrostat diaphragm, of a lever fulcrumed at one end, receiving movement from the diaphragm at an intermediate point and transmitting multiplied 10 movement at its opposite end, and a plunger engaging said opposite end and moved thereby.
4. In a diving gear for a torpedo, the combination with hydrostat, pendulum, engine, valve stem and intervening whiffletree of a connection between the hydrostat diaphragm and whiffletree comprising a lever operated by the diaphragm, a plunger operated by the lever, and a connection between 15 said plunger and the whiffletree whereby the movements of the diaphragm are transmitted thereto.
5. In a diving gear for a torpedo, the combination with hydrostat, pendulum, engine, valve stem and intervening whiffletree of a connection between the hydrostat diaphragm and whiffletree comprising a lever operated by the diaphragm, a plunger operated by the lever, and an elbow lever moved 20 thereby, an attaching ring therefor, and a lever, the fulcrum of which is carried by said ring, and which lever receives movement from the diaphragm.
- 10 6. In a diving gear for a torpedo, the combination with hydrostat, pendulum, engine, valve stem and intervening whiffletree of a connection between the hydrostat diaphragm and whiffletree comprising a lever operated by the diaphragm, a plunger operated by the lever, a rock lever to which the whiffletree is fulcrumed, and a connection from said plunger to said rock lever whereby movements of the diaphragm are 25 transmitted thereto.
7. In a diving gear for a torpedo, the combination with hydrostat, pendulum, engine, valve stem and intervening whiffletree of a connection between the hydrostat diaphragm and whiffletree comprising a lever operated by the diaphragm, a plunger operated by the lever, a rock lever to which the whiffletree is fulcrumed, and connections between said plunger and rock lever, said connections including an adjustable link whereby to adjust the position of the rock lever.
- In witness whereof, I have hereunto signed my name.

WILLIAM DIETER.
